CABLE CLAMP

Arthur W. Buckner, Houston, Tex.

Application February 3, 1938, Serial No. 188,564

1 Claim. (Cl. 24—132)

This invention relates to a novel clamp for securing the ends of cables together.

The primary object of the present invention is to provide a clamp of the above kind which is efficient in use, simple and inexpensive to manufacture, and capable of being quickly and easily placed in use without the exercise of special skill.

More particularly, the present invention relates to an improved cable clamp including a pair of cooperating clamping members having intermediate jaw portions provided with recesses for accommodating the ends of the cables to be clamped together, said clamping members being hinged together at corresponding ends and being provided at their remaining ends with cooperating ears adapted to receive a bolt whereby the clamping members may be effectively drawn and secured together for securely clamping the cable ends therebetween.

A further object of the present invention is to provide a cable clamp of the above character wherein the cable clamping members are of such form and construction as to insure efficient clamping action and to facilitate application of the clamp to the cables.

Other objects and advantages of the present invention will become apparent from the following description when considered in connection with the accompanying drawing, in which:

Figure 1 is a side elevational view of a cable clamp constructed in accordance with the present invention, and illustrating the cable clamp as it appears in use.

Figure 2 is a plan view thereof.

Figure 3 is a side elevational view of one of the clamping members forming part of the cable clamp shown in Figures 1 and 2; and

Figure 4 is a plan view of the other clamping member forming part of the cable clamp shown in Figures 1 and 2.

Referring in detail to the drawing, the present cable clamp consists of a pair of clamping members 5 and 6 having intermediate jaw portions provided at their inner sides with transverse recesses 7 and 8 for accommodating the ends of the cables 9 and 10 to be clamped together. The clamping members 5 and 6 are hingedly connected together at corresponding ends by means of a pivot pin 11 and are provided at their remaining ends with ears 12 and 13 adapted for reception of a bolt 14 having a nut 15 threaded thereon. Obviously, by tightening the nut 14, the clamping members 5 and 6 will be drawn together so as to securely clamp the cables 9 and 10 therebetween. Only one bolt is re-

quired and this may be readily applied or removed for convenience in applying or removing the clamp.

As shown more clearly in Figures 2 and 4, the clamping member 5 is of plate-like form and relatively wide, being formed at one end with spaced knuckles 16. On the other hand, the clamping member 6 is relatively narrow and formed at one end with a single knuckle 17 of a width adapted to be snugly received between the knuckles 16 of the clamping member 5. The hinge pin 11 is inserted in the knuckles 16 and 17 of the clamping members 5 and 6 to hingedly connect them together at their corresponding ends as above noted.

The relatively wide clamping member 5 is formed on each of its hinge knuckles 16 with inwardly projecting horns 18 at one side of the recess 7, and formed on said clamping member 5 at the opposite side of the recess 17, or on the ear 12 are longer inwardly projecting horns or lugs 19. In use, the cable 9 is placed in the recess 7 of the wider clamping member 5 and then the second cable 10 is disposed upon the cable 9 beneath the horns 18 and 19, the latter cable being maintained in proper position while the clamping member 6 is swung into engagement with said cable 19 and connected by the bolt 14 with the clamping member 5. The nut 15 is then applied and tightened so as to securely clamp the cables together in proper parallel contiguous relation, overlapped one upon the other. In order to provide maximum engagement of the clamping member 5 with the surface of the cable 9, the recess 7 of said clamping member 5 is provided with spiral grooves 20 receiving the adjacent strands of the cable 9.

From the foregoing description, it is believed that the construction and manner of use, as well as the advantages of the present invention will be readily understood and appreciated by those skilled in the art. It will be seen that I have provided a very simple and durable cable clamp which will be very efficient for the intended purpose as well as convenient to use. Minor changes in the details of construction illustrated and described are contemplated within the spirit and scope of the invention as claimed.

What I claim as new is:

A cable clamp of the character described comprising a pair of clamping members having outwardly arched intermediate jaw portions provided at their inner sides with opposed transverse recesses for accommodating the ends of the cables to be clamped together, one of said clamp-

ing members being of relatively wide plate-like form and provided at one end with spaced hinge knuckles and at the other end with an ear, the other clamping member being relatively narrow
5 and provided at one end with an ear and at the other end with a single hinge knuckle received between and hinged to the hinge knuckles of the first-named clamping member, inwardly projecting horns on the hinge knuckles and on the ear
10 of said first-named clamping member, said horns

being arranged at opposite sides of said other clamping member and at opposite sides of the recess of said first-named clamping member for retaining the cable ends in proper superimposed relation until clamped together, and a bolt extending through the ears of said clamping members and having a nut threaded thereon to draw said members together.

ARTHUR W. BUCKNER. 10
